Primary Examiner — Rhea Shields

(74) Attorney, Agent, or Firm — Laurence A. Greenberg; Werner H. Stemmer; Ralph E. Locher

(57) **CLAIM**

The ornamental design for a connector, as shown and described.

DESCRIPTION

1. Connector
- 1.1 : Perspective
- 1.2 : Right
- 1.3 : Top
- 1.4 : Left
- 1.5 : Bottom
- 1.6 : Back
- 1.7 : Front

1 Claim, 7 Drawing Sheets(56)
